UNITED STATES PATENT OFFICE

150,805

DESIGN FOR A BAT

Bernard M. Pauly, Springfield, Ohio

Application April 9, 1947, Serial No. 138,262

Term of patent 7 years

(Cl. D34—5)

To all whom it may concern:

Be it known that I, Bernard M. Pauly, a citizen of the United States, residing at Springfield, in the county of Clark and State of Ohio, have invented a new, original, and ornamental Design for a Bat, of which the following is a specification, reference being had to the accompanying drawing, forming part thereof.

Figure 1 is a plan view of a bat, showing my new design, and,

Figure 2 is a side elevational view thereof.

The side of the bat not shown is of substantially the same appearance as the side illustrated.

I claim:

The ornamental design for a bat, as shown and described.

BERNARD M. PAULY.
